CLAIM

The ornamental design for a dashboard camera, as shown and described.

DESCRIPTION

FIG. 1 is a top, front, right side perspective view of a dashboard camera, showing my design.

FIG. 2 is a bottom, rear, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view of thereof; and,

FIG. 8 is a bottom plan view of thereof.

(Continued)

The broken lines shown in the drawings are included for the purpose of illustrating portions of the dashboard camera that form no part of the claimed design.

1 Claim, 8 Drawing Sheets
